CLAMP

Nick J. Anton, Cicero, Ill.

Application April 10, 1935, Serial No. 15,658

2 Claims. (Cl. 15—267)

My invention relates to shoe shining equipment, and has among its objects and advantages the provision of novel means for clamping and holding the shoe in place upon the foot rest during shining operations.

In the accompanying drawing:

Fig. 1 is a perspective view of a shoe anchored to a foot rest through the medium of my invention;

10 Fig. 2 is a sectional view along the line 2—2 of Fig. 1;

Fig. 3 is a sectional view along the line 3—3 of Fig. 2; and

Fig. 4 is a perspective view of the invention.

15 In the embodiment selected to illustrate my invention, I make use of a standard 10 mounted upon a suitable support, not shown, and provided with a foot rest 12. This equipment may be conventional and need not be described in further detail.

20 My invention embodies a device for anchoring the shoe 14 to the foot rest 12. This device comprises spring wire coiled to provide a reach of convolutions 16 arranged to bear against the bottom side of the foot rest 12. One end of the wire is bent to provide a hook 18 arranged to pass over the sole 20 of the shoe 14. This hook comprises two parallel reaches 22 bent at 24 to position the hook 18 inwardly of the reach of convolutions 16.

25 One of the reaches 22 is bent at 26 to arrange a short reach 28 which may be passed between two convolutions of the grip 16. This connection tends to make a more sturdy construction and lends stability to the hook 18.

30 The other end of the wire is bent to provide a ring 30 comprising a number of convolutions. This ring provides a grip for operating purposes. The end of the wire is extended beyond the ring 30 and shaped to provide a hook 32 of the same type as the hook 18. The end of the wire is looped around the convolutions of the ring 30 at 34.

In operation the hook 18 is passed over the sole 20, and the clamp is stretched a sufficient distance to permit the hook 32 to be passed over the sole 20. The ring 30 provides a convenient grip for stretching the clamp and positioning the hook 32 over the sole.

25 My invention embodies a single piece of wire shaped to provide an efficient clamp. This clamp may be associated with shoe shining equipment of conventional design, and the construction eliminates the necessity for adjusting screws, clamp parts, etc. In addition the clamp is of such configuration and small proportions that the device may be carried in the pocket of the user. Thus, the clamp is always available and may be shifted from place to place with little or no inconvenience.

Without further elaboration, the foregoing will so fully explain my invention that others may, by applying current knowledge, readily adapt the 20 same for use under various conditions of service.

I claim:

1. The combination with a foot rest, of a clamp comprising a single piece of extensible material arranged to pass across under the foot rest, and 25 hook means at the ends of said clamp for connection with the sole of a shoe positioned on the foot rest.

2. A shoe clamp comprising a piece of wire shaped to provide a convoluted reach, one end of 30 the wire being shaped to provide a hook comprising two reaches arranged in parallel relation, said reaches being bent back partly over the convoluted reach, one of the reaches having an end anchored between certain of said convolutions, 35 the other end of said wire being shaped to provide a grip part and a hook, said hook comprising two reaches arranged in spaced relation, one of said reaches having its end connected with said grip part.

NICK J. ANTON.
